UNITED STATES PATENT OFFICE.

VINA JONES, OF ABILENE, TEXAS.

CUTTING-TABLE.

SPECIFICATION forming part of Letters Patent No. 495,252, dated April 11, 1893.

Application filed December 9, 1892. Serial No. 454,679. (No model.)

To all whom it may concern:

Be it known that I, VINA JONES, a citizen of the United States, residing at Abilene, in the county of Taylor and State of Texas, 5 have invented certain new and useful Improvements in a Cutting Board or Table for Millinery and Domestic Uses, of which the following is a specification.

My invention has relation to improvements 10 in trimming-tables and the object is to provide a table for conveniently measuring, holding, and cutting or trimming cloths or other fabrics disposed and arranged thereon, as hereinafter set forth.

15 My invention consists in the novel construction and arrangements of the parts and their combination, as will be hereinafter specified, and particularly pointed out in the claim.

20 I have fully and clearly illustrated my invention in the accompanying drawings, wherein—

Figure 1 is a plan view of the table having the graduated measures, and provided with 25 the spring-holders. Fig. 2 is a detail of one of the spring holding devices.

A designates the top of the table, or a board 30 adapted to be laid on a table or otherwise suitably supported. This top or board is of 35 any suitable length, and has marked thereon longitudinally arranged measuring scales 1, 2, divided into such parts as may be requisite and needed. Between these longitudinally arranged measures are parallel lines 3, running the length of the measures and arranged at such distance as may be convenient 40 to indicate divisions of measures transversely between the edge-scales 1 and 2, and to facilitate the securing of the measure and 45 to ascertain the width of the fabric to be cut, the parallel lines are intersected by transversely arranged columns or lines 4, 5, 6, in which are indicated by numerals the distance from the edge-lines, as shown in the drawings.

At the ends of the table or board are 45 detachably secured spring-arms 7, 8; and intermediate between these are similar arms, 9, 10, 11, as may be required. These spring-arms

consist of spring-wires or narrow and thin 50 strips of spring metal, as shown, and are formed with a stem *a*, running parallel with the face of the table, and have an arched portion *b*, terminating in a footpiece *c*, pressing on the face of the table and adapted to 55 press down on the fabric placed on the table and hold it in a position to which it is adjusted thereon. The spring-arms or holding-arms, are held in position by sleeves 12, fixed on the table, to take the stems of the arms in 60 case wires are used to make the arms of; or if the spring-strips are used; then spring tongues or keepers 13, are secured to the table, and the stems of the strips passed under the 65 keepers wherein they are detachably retained. By making the spring-arms detachable they are readily removed from association with the table, their removal leaving the 70 table free for such other uses as may be desired; and by making the arms of the form shown and described, with the arch *b*, a ready hand-hold is presented whereby they may be 75 inserted or removed, and also when adjustment of the fabrics under them is desired or required, they may conveniently be raised up free from the table and the cloth adjusted without tendency to wrinkle or stretch.

The invention is especially useful as a cutting board or table for milliners, but is also 80 equally adapted for domestic purposes. It is designed for use in cutting out upon. The cloth can be made fast down upon the board or table by passing it under the spring-holders, which will hold it in adjusted or arranged position. The cloth may be tacked at the 85 ends to give additional security if desired. The piece to be cut off may be of equal width throughout which is ascertained and measured by the measures; or it may be wider at one end than the other. In either instance 90 the spring-holders clamp and hold the material, while the cut is made along the edge of the board.

Having thus described my invention, what I claim, and desire to secure by Letters Patent, is—

In combination, a trimming-board provided with parallel and transversely arranged in-

dicated measures, keepers secured to the face of the board, and spring-holding arms, detachably secured in the keepers, and consisting of a stem arranged parallel with the face 5 of the board and an arched front portion terminating in a foot-piece adapted to bear on the face of the board, substantially as set forth.

In witness whereof I hereunto set my hand in the presence of two witnesses.

VINA JONES.
